UNITED STATES PATENT OFFICE.

WILLIAM HAAS, OF MILWAUKEE, WISCONSIN.

BALL CATCHER AND THROWER.

1,375,906.

Specification of Letters Patent. Patented Apr. 26, 1921.

Application filed March 9, 1920. Serial No. 364,530.

To all whom it may concern:

Be it known that I, WILLIAM HAAS, a citizen of Germany, residing at Milwaukee, in the county of Milwaukee and State of Wisconsin, have invented certain new and useful Improvements in Ball Catchers and Throwers; and I do hereby declare the following to be a full, clear, and exact description of the invention, such as will enable others skilled in the art to which it appertains to make and use the same.

This invention relates to game apparatus in the form of a ball catcher and thrower and it consists in the novel features herein-
15 after described and claimed herein.

An object of the invention is to provide a device of the character stated which is of simple and durable structure and which may be easily and accurately manipulated for
20 catching a ball on the fly or catching a ball which is rolling and it may also be used for casting the ball.

With this object in view the ball catcher and thrower comprises a member having a handle and provided with a flat head which is provided with a curved end. The head is further provided with a longitudinally disposed opening having an enlargement at its forward or outer end, the said enlargement
25 being circular. The basket structure is attached to one side of the head and is adapted to be used for catching the ball. The opening and the enlargement together with
30 their side edges are adapted to be used for casting or throwing the ball as will be explained.

In the accompanying drawing:

Figure 1 is a perspective view of the ball
35 catcher and thrower.

Fig. 2 is a fragmentary side elevation of the same.

The ball catcher and thrower comprises a member having a handle portion 1 and a head portion 2. The said member preferably made of a strip of wood and the head
45 2 is bounded by an arcuate edge 3. The head portion 2 is provided along its median longitudinal dimension with a slot 4 which
50 communicates at its outer end with a circular opening 5.

A basket 6 is applied to one side of the

head portion 2 and the said basket is made from a single length of wire which includes side portions 7 spaced from each other as at 55 8, the space 8 lying opposite the slot 4 in the head portion 2. The basket does not cover the opening 5.

In use the device may be manipulated as follows: Assuming that a ball is rolling toward a player, the player places the head portion 2 in the path of movement of the ball with the basket under the portion 2 and the portions 1 and 2 upwardly inclined with relation to the path of movement of the ball. 60 When the ball strikes the portion 2 it is deflected in an upward direction and by elevating the device rapidly the ball is cast into the air and as it descends the device may be turned in the hand and the ball may 65 be caught in the basket. If it is desired to remove the ball the fingers may be inserted through the opening 8. If it is desired to throw the ball without removing it from the device, the device is given a cast movement similar to that applied to a tennis racket when it is about to strike a ball, this casting movement will cause the ball to roll along the slot 4 until it arrives at the opening 5. The ball is held by the edges of the 70 opening momentarily and at the final stroke of the cast of the device the ball flies from the same and moves in the direction in which it is directed by the player. 75

Having described the invention what is 80 claimed is:

A ball catcher and thrower comprising a member having a handle portion and a head portion provided with an arcuate edge, the head portion having a longitudinally disposed slot and a circular opening communicating with the slot, a basket applied to one side of the head and consisting of a single piece of wire having side portions lying at the opposite side of the slot in the head portion and leaving the opening in the head portion uncovered. 90 95

In testimony whereof I affix my signature in presence of two witnesses.

WILLIAM HAAS.
